DEWEY H. BITNEY, OF ALBION, MICHIGAN, ASSIGNOR TO UNION STEEL PRODUCTS COMPANY, OF ALBION, MICHIGAN

STRUCTURAL UNIT

Application filed May 21, 1928. Serial No. 279,225.

The main object of this invention is to provide a structural unit for use in attaching floor sleepers, furring or the like to concrete foundations and walls.

5 A further object is to provide a structural unit of the character indicated in which a plurality of attaching members may be simultaneously set or placed in proper spaced relation.

10 A still further object is to provide a structure having these advantages in which the clips or anchoring elements are not likely to be broken off although subject to severe usage prior to their attachment to the part to be anchored.

15 Objects relating to details and economies of construction and operation of my invention will appear from the detailed description to follow. The invention is defined and pointed out in the claim.

A structure which is a preferred embodiment of my invention is illustrated in the accompanying drawing, forming a part of this application, in which:

20 Fig. 1 is a fragmentary perspective view of a concrete wall or foundation having a series of my improved structural units in position therein and attached to the furring or sleepers.

25 Fig. 2 is a detail section.

Fig. 3 is a fragmentary side elevation of one of my improved structural units.

Fig. 4 is a detail section on a line corresponding to line 4—4 of Fig. 3.

30 In the drawing similar reference characters refer to similar parts throughout the several views.

Referring to the drawing, 1 represents a concrete foundation or wall and 2 floor sleepers or furring pieces.

35 In Fig. 1, I show portions of a plurality of my improved structural units, each unit comprising a longitudinal rod 3 of substantial length and a plurality of combined anchoring and attaching members designated generally by the numeral 4.

40 These attaching members are formed of bendable wire and are of a general U-shape, one arm 5 of each member being welded to the longitudinal rod in transverse relation

thereto. The other arm 6 is extended into an angle portion 7 terminating in an eye 8 adapted to receive a nail 9.

45 The members 4, when secured to the rod, are of the form shown in Fig. 3 with the angled attaching member 7 disposed longitudinally of the rod, the members being preferably arranged in pairs as shown in the drawing with the attaching members disposed in opposite directions.

55 The bight portions of the members 4 are adapted to be imbedded in the concrete as shown in Fig. 2, the same being pushed into the concrete while it is in a plastic condition. When it is desired to attach the parts 2, the 60 attaching members 7 are bent to an upright position, as shown in Fig. 2.

65 Thus arranged, the members are not likely to be broken from the rod either when the attaching members are straightened up to operative position or by being stepped on or having a wheel pass over the same or some such fall thereon during the building operations which are usually carried on after the floor foundation has been laid and prior to the 70 laying of the floor.

75 The U-shape of the anchoring legs also serves to provide very efficient anchors.

Having thus described my invention, what I claim as new and desire to secure by Letters 80 Patent, is:

An anchoring unit for concrete structures comprising a longitudinal rod of substantial length, and a plurality of U-shaped combined anchoring and attaching members having 85 one arm longer than the other and angled, said members being disposed transversely of the longitudinal rod and their shorter arms welded thereto, the angled arms being adapted to be bent to upright positions for attachment to the members to be secured, the bight portions of said members constituting anchoring members adapted to be imbedded in a concrete body.

90 In witness whereof I have hereunto set my 95 hand.

DEWEY H. BITNEY.
